UNITED STATES PATENT OFFICE.

JOHN F. O'CONNOR, OF CHICAGO, ILLINOIS, ASSIGNOR TO WILLIAM H. MINER, OF CHAZY,
NEW YORK.

BRAKE FOR RAILWAY CARS.

1,300,458.

Specification of Letters Patent. Patented Apr. 15, 1919.

Application filed October 28, 1916. Serial No. 128,185.

To all whom it may concern:

Be it known that I, JOHN F. O'CONNOR, a citizen of the United States, residing at Chicago, in the county of Cook and State 5 of Illinois, have invented a certain new and useful Improvement in Brakes for Railway-Cars, of which the following is a full, clear, concise, and exact description, reference being had to the accompanying drawings, 10 forming a part of this specification.

My invention relates to improvements in brakes for railway cars.

The object of my invention is to provide a simple and efficient brake.

15 In the drawings forming a part of this specification, Figure 1 is an end elevation of a brake embodying my invention; Fig. 2 is a transverse section taken on line 2—2 of Fig. 3; Fig. 3 is a vertical longitudinal 20 section taken on line 3—3 of Fig. 1; Fig. 4 is a horizontal longitudinal section taken on line 4—4 of Fig. 1; Fig. 5 is a cross section taken on line 5—5 of Fig. 3; Fig. 6 is an enlarged detail of the operating pawl; 25 and Fig. 7 is an enlarged detail of the hanger to which the upper end of the handle is attached.

Referring to the drawings, the numeral 6 indicates a part of a railroad car, as, for 30 instance, the end thereof, to which the brake is adapted to be secured. A casing 7 adapted to contain parts hereinafter described is provided at its inner end with the lugs 8, suitably perforated as at 9 for the passage 35 of suitable means such as the rivets 10 to secure the said casing to a railroad car. At its outer end the casing is provided with a closing member as, for instance, the plate 11, into the end of which the head 12 of a 40 bolt 13 is countersunk, the said bolt passing through the member 6 of the car and being provided at its inner end with the nut 14. Said bolt 13 serves as an axle for the drum 15, the said drum being provided near its ends 45 with the journals 16—16 and being hollow intermediate said journals as indicated at 17. The said drum bears a ratchet 19 provided with the teeth 20—20. It is also provided with a pair of spaced-apart collars 21—21 50 forming an anchorage for the brake chain 22. The ratchet 19, the collars 21 and the portions 23—23 of the drum upon which the brake chain is adapted to be wound are all made integral to give strength to the 55 parts to prevent wear, and the said drum

is hollowed out, as hereinbefore described, and given a journaling near each end upon the axle member in order to prevent binding of the drum upon the axle in the event that through the chain unusual torsion should be 60 applied to said drum in braking. The said casing is provided near its outer end and along its under surface with an opening 24 through which the upper end 25 of the operating handle 26 is adapted to pass. The 65 said handle is provided with an integral, wide pawl 27 which is adapted to be thrown into engagement with the teeth 20 of the ratchet 19, the said handle being suspended in its position by means of the hanger 28, 70 which is of semilunar shape, pivotally connected with the handle by the wide pawl as at 29 at its lower end and extending over the ratchet at its upper end as at 30. The said hanger is provided at either edge with 75 the reinforcing flange 31 and is adapted in the operation of the parts to ride upon the ratchet itself. A holding pawl 32 is pivoted within the casing by means of a hollow lug 33 inwardly extended from the 80 plate 11, said pawl having a handle 35. The said hollow lug 33 is most clearly shown in Fig. 2 of the drawings. One of the collars 21—21 upon the drum is immediately adjacent the ratchet, and at one point, as, for 85 instance, indicated at the numeral 36 in Fig. 3 of the drawings, the drum is provided with a slot which opens into the hollow portion 17 thereof. Extending into said hollow portion and upon the interior of the 90 drum there is provided a lip 38. The purpose of this structure is to permit the insertion through the opening 36 of the end link 37 of the chain 22 and the passage of said link over the said lip, whereupon the bolt 95 13 is passed through the drum and the space between the bolt 13 and the nearest portion of the lip 38 is sufficiently narrow, as indicated at the numeral 39 in Fig. 3 of the 100 drawings, to prevent the withdrawal of the end link of the chain when the bolt 13 is in its position within the drum. By this means the brake chain is securely fastened to the drum and the alternate links upon the end of the chain are received in the space 40 between the collars 21 upon said drum, and the intervening links lie flat upon the edges of said collar on the first winding of the 105 chain upon the drum.

In its normal position, the brake handle 110

26 hangs suspended substantially as shown in Figs. 1 and 2 of the drawings.

In operating the brake, the handle is drawn upwardly in a clockwise direction, 5 the pawl thereon engaging the ratchet and the whole suspended by the hanger, which moves with the ratchet when the operating pawl is engaged therewith. The holding pawl, on account of the weight of the handle 10 thereof, will be in constant engagement with the ratchet during the winding up of the brake drum, and in such winding upon the return of the handle to its normal inoperative position the hanger rides in 15 returning movement upon the ratchet. To release the drum, the holding pawl may be disengaged from the ratchet by means of the handle 35 of said pawl.

I claim:

- 20 1. In a brake, a drum, a ratchet associated therewith, an operating handle, a pawl associated with said handle to engage the ratchet, and a hanger riding upon said ratchet and connected to the handle.
- 25 2. In a brake, an axle, a drum mounted upon said axle, a ratchet associated with said drum, a handle for operating said drum, a pawl associated with said handle and adapted to engage the ratchet, and a 30 hanger for supporting said handle, the said hanger riding upon the ratchet.
- 35 3. In a brake, an axle, a drum mounted thereon, a ratchet connected to said drum, a handle, a pawl associated with said handle to engage the ratchet, and a hanger pivot-

ally connected to said handle, the said hanger riding upon the ratchet.

4. In a brake, an axle, a drum mounted thereon, a toothed ratchet associated with said drum, a handle for operating the 40 ratchet, a pawl to engage the teeth of said ratchet, and a hanger connected to said handle, the said hanger riding upon the teeth of the ratchet.

5. In a brake, in combination, a drum, 45 a brake chain, and an axle passing through the drum, the said drum being provided with an opening for the passage of a link of the chain, the said drum having shoulders over which the said link may be passed 50 through said opening, the axle passing near said link to prevent its removal from said shoulders when the axle is in position.

6. In a winding mechanism, the combination with a casing, of a member rotatably mounted within said casing, said member having a ratchet wheel rotatable in unison therewith, an arcuate hanger loosely mounted on said ratchet wheel and free to oscillate with respect to the latter, an operating lever 60 pivotally attached to said hanger, said lever having a pawl adapted to coöperate with said ratchet wheel.

In witness that I claim the foregoing I have hereunto subscribed my name this 25th 65 day of October 1916.

JOHN F. O'CONNOR.
